DISK OR RING PROJECTOR

Alfred Luthi, Philadelphia, Pa.

Application February 27, 1952, Serial No. 273,576

3 Claims. (Cl. 124—17)

1

My invention relates to a new and amusing game apparatus and has for one of its objects to provide a novel and interesting device of this character requiring considerable skill and some degree of chance in playing several types of games.

Another object of the invention is to produce a game apparatus including the combination of a game piece projector and a target member of unique construction provided with means for indicating a score resulting from an individual play.

Another object of this invention is to provide a game apparatus consisting of target members, a hazard member, and a projector member for propelling a game piece in the form of a cushion rimmed disc or elastic ball, said members being capable of disposition in various relative positions for playing different types of games.

A further object of the present invention is to produce a projector for a game piece of missile which projector includes a pair of spaced and slotted uprights with a rubber band fitted in the slots for attaching it to said uprights in a manner to provide two tensioned strands to be twisted with the missile between them so that when said missile is released it will be propelled with considerable speed.

A still further object of the invention is to form the slots in the uprights in such a way that the strands of the rubber band may be adjusted with relation to each other for changing the trajectory of the missile.

With the above and other objects in view this invention consists of the details of construction and combination of elements hereinafter set forth and then designated by the claims.

In order that those skilled in the art to which this invention appertains may understand how to make and use the same I will describe its construction in detail referring by numerals to the accompanying drawing forming a part hereof, in which:

Fig. 1 is a perspective view of the game apparatus with several elements thereof arranged in preselected positions relative to one another and showing in dotted lines a number of positions of a game piece or missile during its travel over a random path from the projector to the target.

Fig. 2 is a section of the target on the line 2—2 of Fig. 1.

Fig. 3 is an enlarged sectional view of the same on the line 3—3 of Fig. 1.

Fig. 4 is an enlarged top plan view of the projector showing in dotted lines the manner of holding a disc shaped missile in the twisted strands of a rubber band.

2

Fig. 5 is an end view thereof, looking at the left hand end, and showing the means for adjusting the rubber band strands.

Fig. 6 is a perspective view of the projector, on a reduced scale, to illustrate the employment of a ball as a substitute for the disc game piece or missile.

Fig. 7 is a perspective view of the game apparatus having a target of slightly different form from that depicted in Fig. 1.

Fig. 8 is a perspective view of the game apparatus employing a modified type of target member.

Fig. 9 is a section of the hazard member on the line 9—9 of Fig. 8.

Fig. 10 is a face view of the disc shaped, cushion rimmed game piece or missile.

In carrying out my invention as herein embodied 15 represents the projector produced from any suitable material having sufficient stiffness or rigidity to retain its form and includes a base 16 of appropriate dimensions, to retain the device firmly on a support while in use. The base is preferably of oblong shape and uprights 17 project upwardly therefrom at both ends which uprights are braced by angular struts 18 extending from the upper ends of said uprights laterally to said base 16 in a convergent manner but being spaced apart an appreciable distance.

20 The uprights 17 are also of angular formation with the larger ends at the bottoms and a pair of parallel slots 19, 20 are formed in each of said uprights and run from the rear angular edge or hypotenuse to a location short of but adjacent to the forward portions of said uprights.

25 A rubber band 21 is adjustably mounted in said uprights which are placed to provide some tension on the strands of said rubber band that stretch across the space between the two uprights. By 30 moving the lower strand to various positions along the lower slot 20 the missile, to be presently described, can initially be directed at different angles to the plane of the base of the projector.

35 A missile or game piece 22 may consist of a disc of any suitable material but, preferably, includes a disc shaped body 23, Fig. 10, having an elastic perimeter 24. Instead of a disc the missile may be a rubber or other rather soft ball 25, as shown in Fig. 6. In any case the missile must be of curved formation to readily roll over playing surfaces.

40 To propel a missile, the latter is placed between the two strands of the rubber band and said strands twisted clockwise, when viewing Fig. 5, until the missile is firmly held between the rubber band strands and the desired tension is

obtained on said strands. Upon release of the missile, the strands of the rubber band will unwind and impart a rotary motion to said missile so that as it leaves the rubber band it will drop to a surface and roll thereon in a direction substantially in a preselected path but to some extent in a random direction.

The projector is placed on any suitable surface, such as a floor or the top of a table and in front of said projector, some distance therefrom, is positioned a hazard member 26 including a convexly curved top surface 27 and end rests 28. The inclination of the curved top surface is steeper at one side than at the other to produce different degrees of jumping motions depending upon which inclined portion of the curved surface is first encountered by the missile propelled from the projector. Either inclined portion of said curved surface can be arranged to face the projector by merely reversing the hazard member 28.

Beyond the hazard member 26 at any desirable distance therefrom is placed one of the target members 29, 29a or 29b. The target member 29, Figs. 1, 2 and 3 includes a base 30 with a perpendicular front wall 31 having apertures 32 of sufficient dimensions for the passage of a missile and a numerical indicia 33 is associated with each aperture to represent the value of a play made through a respective aperture. On the base is also mounted an imperforate back wall 34 spaced a distance, at least equal to the diameter of a missile, from the front wall. At the ends of the back wall are forwardly projecting spreading wings 35 and said back wall and its wings are strengthened by braces 36. Between the front and back walls are located a plurality of spaced partitions 37 and positioned between adjacent apertures to form pockets or stalls for temporarily retaining a missile rolled through any aperture. The partitions have deep notches 38 open at the tops whereby a missile in any pocket or stall may be easily grasped between the thumb and forefinger and lifted out of its pocket or stall. This target member is particularly adapted for use on a table or other restricted surface to prevent the missile going astray after entering one of the pockets or stalls.

The target member 29a illustrated in Fig. 7 is similar to that above described but includes only a base 30a and a perpendicular front wall 31a having apertures 32a with which the numerical indicia 33a are associated. The front wall 31a may be braced by rearwardly projecting end wings 39 secured to the base.

A modified form of target member 29a may be substituted for the other target members and as herein shown consists of a number of side by side parallel alleys 40, each including a bottom 41 with a steep incline at the entrance end and a less sharply inclined major portion beyond the entrance in which major portion are formed a number of concave pockets 42 having certain predetermined playing values.

Various types of games can be played such as, for example, baseball, football, golf, racing and similar amusements, and the player using the projector represents the batter, kicker, hitter, runner and the like, and one who, in a predetermined number of plays, makes the highest total score becomes the winner of the game. The apparatus is highly amusing because any one of the

several types of target members can be employed with or without the hazard member and when the latter is used it can be turned to present either degree of inclined surface desired. Considerable skill also is involved in the use of the projector because the strands of the rubber band may be wound up or twisted about one another more or less to regulate the speed of the missile and the direction of said missile can be controlled by turning it on its vertical axis as well as by adjusting the strands of the rubber band in their slots whereby the lower strand will be directly under the upper strand or any desired distance to the front or rear of said upper strand.

Of course I do not wish to be limited to the exact details of construction herein shown and described as these may be varied within the scope of the appended claims without departing from the spirit of my invention.

Having described my invention what I claim as new and useful is:

1. A game apparatus comprising a missile, a projector to propel said missile along a surface, said projector consisting of a base, a pair of spaced uprights on said base and each having a pair of spaced substantially horizontal slots with their open ends at the rear of said uprights, and an endless rubber band inserted in both slots of both uprights to provide two strands extending across the space between the uprights, said strands to be twisted together on both sides of the missile with the latter between them.

2. In a game apparatus, a projector comprising a base, a pair of spaced vertical uprights on said base and each of said uprights having a pair of vertically spaced substantially horizontal slots extending from the rear edge thereof, and an endless rubber band inserted in both slots of both uprights and of a length to provide two strands one above the other under slight tension extending across the space between said uprights, said strands to engage the periphery of a round missile and be twisted together at both sides of said missile to temporarily retain the missile between said strands approximately midway between said spaced uprights.

3. In a game apparatus, a projector including a base, a pair of spaced uprights extending from said base, a pair of rubber strands having pliable and elastic properties attached to the uprights and extending across the space between said uprights with one strand above the other in spaced relation and under slight tension, and a disc shaped missile temporarily held between said rubber strands by engagement of the latter with the periphery of said missile at substantially diametrically opposite points with said strands twisted about one another between the missile and each upright.

ALFRED LUTHI.
